COLLOCATING APPARATUS FOR MAKING CORRECTIONS, ALTERATIONS, AND ADDITIONS ON A PHOTO-TYPE COMPOSED FILM OR SHEET

Stephen Leslie Somerville, South Merstham, and Robert Philip Urry, Reigate, England, and Bernard R. Halpern, Swarthmore, Pa., assignors to The Monotype Corporation Limited, London, England, a British corporation

Application May 14, 1954, Serial No. 429,878

4 Claims. (Cl. 33—184.5)

This invention relates to a method of and apparatus for making corrections, alterations or additions on a film or the like bearing photo-composed type. The film may be an ordinary film bearing a layer of developed and fixed photo-sensitive emulsion or may be a stripping film consisting of a thin sensitised film adhesively secured to a base of transparent film or paper or other suitable material.

In some systems of type design, the characters are all aligned on a standard base line whereas in other systems the characters are all designed on a standard centre or body line. An object of the present invention is to provide an improved method of and apparatus for making corrections, alterations or additions on a film or the like bearing photo-composed type which is applicable to both systems of type design.

In the method according to the invention, a portion of film bearing a required image is substituted in place of a corresponding portion of the film or the like and the image, which is usually a line of photo-composed type, is located in predetermined relation to a datum, or basic gauge for the purpose of cutting out and substitution, by reference to the top and bottom bounding edges of the image, that is to say relatively to two imaginary parallel lines which delineate the tops of the ascenders and the bottoms of the descenders of the characters of a line.

The invention is primarily intended for substituting one or more lines of photo-composed type for one or more other lines of photo-composed type for the purpose of correction or alteration of the text but the invention may also be used to insert a line of photo-composed type in a desired position on a blank portion of the film or the like.

In order that the invention may be clearly understood it will now be described with reference to the accompanying drawings which show, by way of example, one form of construction of apparatus according to the invention.

An apparatus or mechanism for carrying the invention into effect will now be described with reference to the drawings:

Fig. 1 is a plan view of apparatus according to the invention.

Fig. 2 is a section on the line II—II of Fig. 1.

Fig. 3 is a section on the line III—III of Fig. 1.

Figs. 4 and 5 are plan views of details of the apparatus, and

Fig. 6 is a side elevation and Fig. 7 a front elevation of a suitable tool for use with the described apparatus.

Referring to the drawings, the apparatus comprises a table A having a straight edge A¹ along one side thereof of which straight edge projects slightly above the surface of the table (as can be seen more clearly in Fig. 2) in order to locate a side edge of a film or the like placed upon the table A. The table is also provided with a second straight edge A² on the other side thereof. The table is slidable in the direction of the straight edges

2

relative to a supporting frame A³ of which longitudinal side members are provided with guiding ledges a, a¹ and cover strips A⁴, A⁵ which together form guide channels for the side edges of the table A.

On its underside the table is furnished with a rack A⁶ with which meshes a pinion A⁷ fixed to a shaft A⁸ extending transversely across the frame A³ and passing through bearings in the side members thereof. Secured to one end of the shaft A⁸ is a turning drum A⁹ and to the other end a collar A¹⁰ having a knurled flange A¹¹ and screw threaded internally to co-operate with a corresponding screw thread on the end of the shaft A⁸ as indicated at a². A retaining nut A¹² is welded to the end of the shaft A⁸. Pinion A⁷ is furnished with a flange a³ which is arranged to press against the rack A⁶ and lock the table A against sliding movement when the knurled flange A¹¹ is rotated to screw up the collar A¹⁰ on the shaft A⁸ and cause it to press against the side member of the frame A³ and so pull the shaft A⁸ to the left as viewed in Fig. 2.

The frame A³ is provided at opposite sides with pins B and B¹ arranged on a line perpendicular to the direction of the straight edges A¹ and A² of the table A, and which serve to locate a sighting or locating mechanism now to be described.

The sighting mechanism consists of two parts B² and B³. Part B² has a sighting aperture b defined on two opposite sides by two spaced apart parallel bars B⁴ and B⁵ provided at their bottom inner edges with ledges b¹, b². Bar B⁵ is integral with or fixed to the base B² and the latter is formed with holes b³, b⁴ which co-operate with the pins B, B¹ to locate the sighting mechanism with the bar B⁵ perpendicular to the straight edges A¹, A² on the table A. The pins B, B¹ have portions of enlarged diameter, which fit into the holes b³, b⁴, and with shanks which fit into corresponding holes in the frame A³. The shank of pin B¹ is eccentric with respect to its enlarged portion and the latter is provided with a hole b⁵ for receiving the end of a small pin by which the pin B¹ can be rotated about the eccentric axis of its shank to adjust the members B² and B³ angularly about the pin B. The bar B⁴ is carried on the bar B⁵ by means of countersunk studs B⁶ passing through apertures in the bar B⁵ and secured by retaining nuts B⁷. Gauging distance pieces or point blocks B⁸ are provided for determining the spacing of the bars B⁴ and B⁵. For the purpose hereinafter to appear, these distance pieces or point blocks B⁸, can be of different thicknesses so that the inner edges of the ledges b¹ and b² of the bars B⁴ and B⁵ can be spaced apart by varying distances depending upon the body size or "point" size of the photo-composed type to be corrected or altered or added to the text. The part B³ is provided with a straight edge B⁹ and is formed with holes b⁶ and b⁷ which co-operate with the pins B and B¹ to hold the part B³ with its straight edge B⁹ perpendicular to the straight edges A¹ and A² of the table A. The hole b⁷ is open at the end so as to permit the insertion of the turning pin in the pin B¹ for the purpose of angular adjustment of the parts B² and B³.

A tool for use in manipulating the desired portions on the emulsion-bearing portions of the original and the substituting films and in conjunction with the above described apparatus is illustrated in Figs 6 and 7 and consists of a bar C preferably of steel having a cutting edge c at one end which is slightly inset from the plane of one face of the tool. The other end of the tool, or if desired a separate tool, is provided with a stripping hook c¹ and with a scraping edge c² for purposes hereinafter to appear. A number of tools C is provided having different thicknesses for fitting with a very close running clearance in the varied widths of the aperture

between the guide faces of the vertical tool and of the bars B^4 and B^5 into different widths of the aperture b according to the body size of the type being dealt with. The end of the tool carrying the hook c^1 and scraping edge c^2 is cut away on opposite faces as indicated at c^3 so that the hook and scraping edge can fit between the inner edges of the ledges b^1 , b^2 .

The apparatus and tools are used as follows:

A stripping film bearing slightly spaced lines of photo-composed type set at right angles to a straight side edge of the film and at a fixed marginal distance therefrom which it is desired to substitute in place of lines of photo-composed type on the original film or the like to be corrected or altered, or which are to be added to said film, is placed emulsion-side up upon the table A and the side edge of the stripping film is located against the straight edge A^1 of the table A so that the lines of photo-composed type extend horizontally or at right angles to the straight edge and at a fixed marginal distance from the table straight edge A^1 . The film is secured in place on the table in any convenient manner, for example by means of adhesive strips or by means of suitable clamps which may if desired be provided on the table. The parts B^2 and B^3 of the sighting or locating mechanism are located on the pins B and B^1 and the drum A^9 is turned to slide the table along the frame A^3 until the image of the first required line of photo-composed type is exactly framed in the aperture b of the sighting mechanism. The top and bottom edge of the aperture b are defined by the inner edges of the ledges b^1 and b^2 of the bars B^4 and B^5 and as previously explained these bars have been spaced apart by gauging distance pieces B^8 which are of a thickness appropriate to the body size of the type so that the top and bottom bounding edges of the image delineating the tops of the ascenders and the bottom of the descenders can be framed within the aperture b . The required image is thereby located in predetermined relation to a datum or basic gauge consisting of the locating pins B, B^1 on the frame and the straight edge A^1 on the table. A cutting tool C of appropriate thickness is then inserted in the aperture b and guided by the vertical faces of the bars B^4 and B^5 makes incisions in the emulsion-bearing component of the stripping film by running the cutting edge c along the edge b^1 of the aperture under light pressure sufficient to cut through only the emulsion-bearing component of the film and leaving the supporting backing thereof untouched and then reversing the tool and running it similarly along the edge b^2 of the part B^5 . Part B^2 of the sighting mechanism is then moved away from part B^3 by rocking, turning the part B^2 about the pin B. If desired the straight edge B^9 may be provided on the part B^2 and the bars B^4 and B^5 may be made to rock backwardly about transverse pivots so as to give access to the film and to the straight edge B^9 . Having removed the bars B^4 and B^5 , transverse incisions are made at the ends of the line of photo-composed type and one end of the portion thus cut out from the emulsion-bearing component of the stripping film is freed from the base of the stripping film by means of any suitable sharp bladed instrument. A strip of film of other transparent material bearing a pressure sensitive adhesive of greater adhesive strength than that holding the emulsion-bearing component of the stripping film to the base thereof is then placed over the cut out portion bearing the desired image and is located against the straight edge A^1 of the table and against the straight edge B^9 of the part B^3 of the sighting mechanism so that this adhesive strip, hereinafter referred to as the transfer strip, is positioned in predetermined relation to the datum consisting of the locating pins B and B^1 and the straight edge A^1 . Pressure is then applied to the transfer strip to adhesively attach thereto temporarily the cut out or severed portion of film component bearing the re-

quired matter. The transfer strip is then peeled off together with the required image bearing portion of film component adhesively attached thereto. A coating of quick-drying pressure adhesive is then applied to the temporarily free underside of this required image-bearing portion of film component and this adhesive is of greater adhesive strength than that of the pressure sensitive adhesive of the transfer strip. The freshly applied adhesive is then covered with a suitable glassine paper and the transfer strip with the attached image-bearing portion of the substitute film is then placed upon a suitable support. If more lines than one are to be substituted on the original film, these further lines are similarly dealt with and placed in order on the said support.

When all the other correction or other desired lines have thus been dealt with, the original film or the like bearing the text to be corrected or altered or added to is then placed in position emulsion-side up on the table A with one longitudinal edge located against the straight edge A^1 of the table. Part B^2 of the sighting mechanism is replaced on the pin B^1 and the drum A^9 is turned so as to sight or locate within the aperture b the first line of photo-composed type to be removed, or the portion of film to bear additional matter as the the case may be. The portion to be replaced is thus disposed in the same relation to the datum consisting of the pins B, B^1 and straight edge A^1 as that previously bearing the required image on the correction or substitute film. The portion to be replaced is now removed either by scraping away only the emulsion bearing member of the film, by means of the scraping edge c^2 of the tool C inserted in the aperture b , or by stripping off only the emulsion-bearing component by means of the hook c^1 in the event of the film or the like being of the stripping type. In this latter case the separation is performed by inserting the sharp hookshaped edge C^1 of the tool between the emulsion-bearing component and the base component of the film under light pressure at the edge of the film beyond the printed area and stripping off from the base member of the film, the portion of the emulsion-bearing part thereof to be replaced, by means of the shearing action of the corners of the tool edge C^2 against the shearing lips b^1 and b^2 of the bars B^4 and B^5 . Part B^2 of the sighting mechanism is then removed and the appropriate transfer strip with the required portion of the substitute film is then located against the straight edges A^1 and B^9 so that this transfer strip and film re-occupy the position it originally occupied in relation to the datum so that the required image-bearing portion of the substitute film is caused to occupy the space vacated by the portion removed of the original film, the protective glassine strip having first been removed from the transfer strip. Pressure is now applied to the transfer strip to adhesively secure the required image-bearing portion to the substitute film or the like to the base or backing of the original film. The transfer strip is then removed, leaving the required image-bearing portion in accurate alignment and register with the body of the photo-composed matter on the original film.

A similar method to that described above is employed where two or more lines are to be removed together and replaced by the same or a different number of other lines. In such a case the sighting mechanism is first positioned to sight the top or bottom bounding edge of the matter to be dealt with and a corresponding incision is made and the table is then moved to sight the other bounding edge of the image and the other incision is then made.

What we claim is:

1. Apparatus for making corrections, alterations and additions on a film bearing lines of photo-composed type, including in combination a table having a straight edge arranged to locate a side edge of a film, a supporting frame on which the table is linearly movable, means

for linearly moving the table on the frame and for securing the table against movement on the frame, and sighting means for accurately indicating the position of the film carried by the relatively movable table comprising a pair of members having straight edges, means for locating the pair of members on the supporting frame, above and immediately adjacent the film on the table with the straight edges substantially normal to the straight edge of the table, and replaceable spacing members at the ends of said pair of members whereby the straight edges of said pair of members may be variably spaced in parallelism with each other.

2. Apparatus as claimed in claim 1, in which the replaceable spacing members are gauge blocks and the pair of members are clamped together by threaded means adjacent the gauge blocks.

3. Apparatus as claimed in claim 1, in which the locating means comprise a pair of pins, upwardly extending from the frame, one at either side of the table, and engageable in holes in the sighting means, one of said pins being rotatable about an eccentric axis whereby

a slight angular adjustment may be given to the parallel straight edges of the pair of members.

4. Apparatus as claimed in claim 1, in which the pair of members comprising the sighting means are provided with straight adjacent sides parallel to each other and to said straight edges forming a wider slot than the space between said straight edges whereby a cutting knife may be received between said adjacent sides and accurately guided for cutting the film on the table.
